UNITED STATES PATENT OFFICE.

JEAN F. WEBB, JR., OF NEW YORK, N. Y., ASSIGNOR TO THE INTERNATIONAL SIGNAL COMPANY, OF NEW YORK, N. Y., A CORPORATION.

TRAIN CONTROLLING AND STOPPING SYSTEM.

1,125,419.

specification of Letters Patent. - Patented Jan. 19, 1915.

Application filed April 27, 1914. Serial No. 834,865.

To all whom it may concern:

Be it known that I, JEAN F. WEBB, Jr., residing at New York, in the county of New York and State of New York, have invented 5 certain new and useful Improvements in Train Controlling and Stopping Systems, of which the following is a specification.

In my application Serial No. 671,859, filed on the 18th day of January, 1912, I have disclosed 10 a train controlling and stopping system that embodies generically a train carried apparatus in which is an air valve that communicates with the train pipe of the air brake system and is normally held in its closed position by suitable devices that 15 cooperate with the valve stem, the holding devices being releasable by a plunger that engages a fixed track stop or tripping ramp along the right of way. The train carried mechanism also includes an automatic resetting device which, when operated by a controlled track fixture, resets the holding devices, thereby closing the air valve and preventing 20 its further action. In practice the controlled track fixture is set a predetermined distance from the tripping ramp to reset the air valve and its holding device almost instantly after the plunger has engaged and left the tripping ramp, to release 25 the holding devices. In this manner, the application of the brakes, unless the controlled track fixture be in its "danger" position, does not take place. If the controlled track fixture be in its "danger" position, the resetting devices do not come into 30 action, and after the fixed ramp is passed by the releasing plunger, the air valve will remain open and permit the application of the brakes. In that application I have also disclosed 35 a manually operative device that cooperates with the resetting mechanism of the train carried fixture, whereby the engineer may reset the same from the cab, subject, however, to the action of a speed controlled lock that prevents the operation of the manual resetting device when the speed 40 of the train is above a predetermined minimum.

The apparatus which forms the subject- 50 matter of this application contains the same generic matter above referred to. The present invention, however, comprises certain improvements in the apparatus which render it more effective and reliable, the object

being to simplify the construction of the apparatus, strengthen the parts, provide means for automatically removing snow and ice from the path of the shoe so that the operation of the apparatus may not be impaired, and to generally improve the construction of 55 the parts.

Again, the present invention includes certain improvements in the construction of the speed governed latch device, and it also includes an improved mechanism whereby, 60 when the automatic apparatus is in operation, the connection between the main air reservoir and the train pipe proper of the air brake system, in which connection the engineer's valve and the double-heading 65 valve are located, is automatically interrupted so as to render the engineer's control 70 inoperative until the automatic apparatus has been reset, and at the same time to cut off the communication between the apparatus and the main reservoir in such a way 75 that the main reservoir pressure will not be unnecessarily lost.

In its more detailed nature, the invention includes those novel details of construction, 80 combination and arrangement of parts, all of which will be first fully described, then be specifically pointed out in the appended claims, and illustrated in the accompanying drawings, in which:—

Figure 1 is a front elevation of the train carried apparatus, the cover plate of the housing being removed and a part of the plunger support and the plunger being shown in section. Fig. 2 is a vertical section on the line 2—2 of Fig. 1. Fig. 3 is a horizontal section on the line 3—3 of Fig. 1. Fig. 4 is a detail enlarged vertical section of the plunger head. Fig. 5 is a rear elevation of the same. Fig. 6 is a horizontal section 90 on the line 6—6 of Fig. 4. Fig. 7 is a detail view of the oscillatable shaft cam finger. Fig. 8 is a detail vertical cross section on the line 8—8 of Fig. 3. Fig. 9 is a cross section 95 on the line 9—9 of Fig. 2. Fig. 10 is a detail cross section on line 10—10 on Fig. 2. Fig. 11 is a rear elevation of the speed controlled latch mechanism. Fig. 12 is a top plan view 100 of the same. Fig. 13 is an enlarged side elevation of the improved valve mechanism, the upper cover section being removed. Fig. 14 is a side elevation of the same. Fig. 15 is an enlarged vertical section on the line

15—15 on Fig. 13. Fig. 16 is a detail perspective view of the valve which controls the passage between the train pipe air chamber and the exhaust air chamber. Fig. 17 5 is a detail perspective view of the valve which controls communication between the main reservoir chamber and the train pipe air chamber of the valve mechanism. Fig. 18 is a diagrammatic view illustrating the 10 connection between the valve mechanism of my apparatus, and the air brake system of the train. Fig. 19 is a view similar to Fig. 15, showing a modification employing a swinging plunger support similar to the form shown in my application aforesaid. Fig. 20 is a detail view of a modification of the shoe.

In the drawings, in which like letters and numerals indicate like parts in all of the 20 figures, 1 represents the housing of the main portion of the train carried apparatus, the front of which is preferably provided with a removable door or cover 2, and the housing is also provided with a depending plunger 25 support 3, which may be integrally formed, as shown in Figs. 1, and 2, or separately formed and mounted on a pivot, as shown in Fig. 19, in a manner similar to that disclosed in my application first aforesaid.

30 4 designates the forwardly projecting support for the balanced oscillatable shaft 49. This shaft is of substantially the same construction as that disclosed in my Patent #1033970, issued on the 30th day of July, 35 1912, and in the present application I make no claim, *per se*, to such shaft construction, as it, *per se*, constitutes no part of the present invention.

The housing 2 has oppositely disposed internal bosses 5 to receive the bearing bushings 6 that are carried by the valve operating cam shaft 7, the said shaft 7 being keyed at 8 to the bushings 6 and also to the multiple cam 9. The cam 9 has three distinct 45 operative parts: the part 10 coöperating with the cam finger 53 (hereinafter referred to), the part 11 coöperating with the plunger 27 and the part 12 coöperating with the latch 14, the part 12 being in the nature of 50 an arm whose end is provided with a latch receiving notch 13.

15 is a rod that is reciprocably mounted in suitable bearing apertures to be moved in a direction transverse to the direction of the 55 shaft 7, and the rod 15 is provided with a head 16 which is dove-tailed into a guideway 20 that forms a guide and support for the head. The head 16 is cutaway at one side to leave stops 17 and 18 between which the cam 60 arm member 12 lies. 19 is another stop carried by the head 16 to engage the supporting guideway 20 to limit the movement of the rod 15 in the resetting direction; the rod 15 being normally pushed in the opposite direction by a spring 21. The rod 15 projects

through bearings in the speed controlled latch housing 119 and has a threaded end 23 onto which the engineer's control rod (not shown) may be attached. The rod 15 is also provided with a notch 22 for a purpose later explained. The housing 2 at the bore for the shaft 7 and its bushings 6, is closed by a suitable plug 24 (see Fig. 1) and there are provided suitable lugs 25, through the medium of which the mechanism may be supported on the engine, preferably beneath the buffer beam adjacent to the pilot.

The support 3 is bored at 26 to receive the plunger 27. The plunger 27 is of the reciprocating type and has a stem 28 whose upper end is threaded at 29 to tap into the threaded bore of the head section 37, the stem 28 being flattened at 30 where it passes through the opening in the bottom of the housing 2 so as to prevent swiveling of the plunger 27. The plunger 27 is held downwardly by a suitable spring 29 and is provided at its lower end with a shoe 30 of a peculiar construction which forms one of the essential improvements embodied in this invention. The shoe 30 is united with the plunger 27 by a thin portion 31, which is designed to break in the event of undue strains so as not to ruin the plunger proper.

32 is a bore which extends shown through the plunger proper 27, through the thin portion 31 and a short distance into the shoe 30. The purpose of this bore will be later explained.

The shoe 30 which, as before stated, forms one of the essential improvements of the present invention, is in the nature of a flat plate, the front face 33 of which is beveled upwardly and backwardly and preferably from the inner side toward the outer side, so as to form a knife or plow-like member to shear off any snow and ice that may accumulate on the path through which the shoe moves and throw it to one side. The outer side of the shoe 30 is also similarly beveled vertically and inwardly, as best shown in Fig. 1, or the beveling may be double, as indicated in Fig. 29. Another feature of the shoe is that the under face of it is preferably not in a true horizontal plane, but is located in a plane that slants forwardly and upwardly a slight distance from the horizontal, whereby the front edge 34 of the shoe will be slightly elevated from contact with the ramp and thereby prevent the front sharp knife edge of the shoe from being dulled by contact with the ramp, the horizontal plane being indicated in Fig. 2 by dot and dash line 35.

I find it advantageous to make the head of the plunger in two sections 37—44 and pivot the same together. This construction is best illustrated in Figs. 4 and 5 of the drawings, by reference to which it will be seen that the section 37 is threaded onto the 130

upper end of the stem 28, and has a rearwardly projecting lug 39 that is straddled by the lugs 40 of the section 44, the lugs 39—40 being pivotally secured by a cross pin 41. 5 43 is a bridge piece across from one side 42 to the other at the lugs 40 to strengthen the same.

The upper section 44 is adapted to engage the cam section 11 and the sections 44—37 10 are normally held in contact, as shown in Fig. 4, by gravity, preferably assisted by a spring 45 projecting downwardly against the flat side 36 and serving as a lock for the section 37, to prevent its 15 turning when once threaded home, the spring 45 having laterally projecting ears 46 which are secured to lugs 47 on the member 37, by cotter pins 48 or other suitable means, as shown in Figs. 2 and 6 of the 20 drawings.

49 is the balanced oscillatable shaft, the construction of which is best disclosed in my patent above referred to, and in Fig. 3 of the present drawings, and a further reference thereto will be made latter. The shaft 49 projects into the housing 2 and carries a disk 50 (see Figs. 1, 2, 3 and 7). The disk 50 is pinned to the shaft 49, as best indicated in Figs. 1 and 2 of the drawings, so as to turn with it and it is provided with a member 51 that forms a stop for engaging the heel of the cam finger 53 which is pivoted on a stud 54 that is fastened by a set screw 55 in the disk 50. The projection 51 and 35 the cam finger 53 are provided with parallelly disposed projections 52—56 respectively between which a coil spring 57 is held to normally retain the cam finger 53 in the position best indicated in Fig. 7 of the 40 drawings.

The plunger 27 has its stem 28 threaded at 58 to receive a bushing 59, to which the pipe line 60 from the valve mechanism is secured.

61 is the resetting trip arm which is carried by the shaft 49, and is provided with buffer members 62 to engage the controlled track fixture (not shown) to reset the mechanism.

The improved valve mechanism which, 50 *per se*, forms the subject-matter of a separate application filed on even date herewith, Serial No 834866, is best illustrated in Figs. 13 to 17 inclusive, and by reference to these figures it will be observed that the valve mechanism includes the main or lower section 63, the relatively permanently held upper section 66, and the removable cover 63 therefor. The upper and lower sections 65—66 are provided with lugs 64 through 60 which the fastening screws that fasten the valve mechanism to the housing 2 may be passed. The lower and upper sections 65—66 are also provided with lugs 67 to receive the fastening screws 68 that hold the 65 parts together. The upper section 66 is pro-

vided with a bearing post 69 to receive one of the bushings 6 of the shaft 7, which shaft has its end projecting into the valve mechanism housing, as best shown in Figs. 13—15.

The lower section of the valve mechanism 70 housing includes two openings 70, one of which is adapted to be plugged, (see Fig. 13) and the other is adapted to receive the connection 117 that leads to the train pipe proper 118. It is also provided with a main entrance 71, into which the pipe connection 116 from the double-heading valve 115 is tapped. In addition to the openings 70—71, two other openings 72—73 are provided, the opening 72 being the one into which the piping 60 is tapped to lead air to the bore 82 of the plunger 27 while the other one 73 is provided for the reception of the pipe 111 that delivers to the whistle 112, or other suitable signal.

The lower section of the valve mechanism incloses three distinct chambers 74—75—76, the chamber 74 being what I shall, for convenience, term, the main-reservoir-air chamber, the chamber 75, I shall term the train-pipe-air chamber, and the other chamber 76, I shall term the exhaust-air chamber. It is understood that this terminology is used particularly for the purpose of convenient reference and is not used in the sense of limitation.

77 is a stuffing box plug that is threaded into the upper end of the lower section 65 to close the chamber 76 at its upper extremity and the plug 77 is bored and provided with a gland 78 and packing 80 to form an air-tight joint where the stem 79 passes through the same. The stem 79 is reduced to receive the head 82 which is pinned to the end 81 of the stem, and is provided with a fork 83 to straddle the collar 89 that is pinned at 90 to the shaft 7 and thereby prevent lateral movement of the head 82. The head 82 is also forked at 85 to straddle the cam 88 that is keyed to the shaft 7 and in the fork 83 there is located a roller 86 on a spindle 87 to engage the cam 88. The purpose of the cam 88 is to normally hold the stem 79 depressed. At the lower end of the stem 79 and in the chamber 76 there is located a cup 91 which is formed with the stem 79 and has a vertically elongated opening 92 for the pin 93 which is carried by a second cup 94 that telescopes within the cup 91, a spring 95, located in the cups, normally presses the cups apart.

98 is the valve which controls communication between the chambers 75 and 76. This valve, under normal conditions, is held closed by the engagement of a pin 96 which it carries in its bore 97, with the under face of the cup 94. The valve 98 has a stem 99 which projects into the bore 100 of the tubular stem 101 of the main valve 102. The valve 102 controls communication between 125

the chambers 74-75. The valves 102 and 98 are so arranged that when one is closed the other is open, and vice versa. The valve stem 101-99 are secured together by a suitable seter pin passed through the holes 105-106 and the valve 102 has its stem 101 guided in the valve seat passages by lugs 103-104.

107 is a plug tapped into the bottom of the valve casing to close the bottom opening into the chamber 74. The plug 107 is half-cupped as at 108 to form a moisture condensation receptacle to prevent a surplus of water of condensation from accumulating in the chamber 74 and possibly freezing up the valve 102. The plug 107 has a stem 109 that projects up into close proximity to the valve 102 and a spring 110 surrounds the stem 109 and continuously tends to seat the valve 102 (and consequently unseat the valve 98).

113 (see Fig. 18) designates the main air reservoir which is piped up with the engineer's valve 114 by a connection 116, the connection 113 continuing from the engineer's valve to the train pipe proper 118, under normal conditions, via the double-bending valve 115. When my invention is employed, the connection between the double-bending valve 115 and the train pipe 118 is cut and connected with my apparatus as hereinbefore described, and as indicated diagrammatically in Fig. 18.

119 is the main supporting housing for the speed controlled governor mechanism, the purpose of which is to lock the rod 23 from operation whenever the speed of the train is above a predetermined minimum. In my present construction of latch mechanism, the housing 119 is provided with removable side plates 121, whereby access to the interior may be readily had, and it is provided with bearings 120 for the rod. By reference particularly to Figs. 2, 9, 11 and 12, the construction of this mechanism will be best understood.

122 is a bearing cap which is secured on the housing 119 and which supports the drive shaft 124 which extends to and is geared up in any suitable manner with a rotating part of the train (not shown), as for example, the axle of the front truck of the locomotive. The shaft 124 is coupled at 125 to the governor shaft 126. The shaft 126 is provided with collars 127 to prevent endwise movement and it runs in ball bearings 128 carried by the frame or housing 119.

129 is a plug that is inserted into the bottom of the housing 119 to close the same.

On the shaft 126 there is located a sleeve 130 which is adapted for longitudinal movement on the shaft under the influence of the centrifugal governor balls 132. The balls 132 are pivotally mounted at 133 on

a pin 131, which is carried by the shaft 126 and passes through slots in the sleeve 130. The balls 132 have lugs 134 to which the links 135 that connect the balls 132 of the sleeve 130 are fastened.

138 is the weighted latch member. In the preferred construction this member is made in duplicate halves fastened together by suitable fastenings 142 and provided with bearings 139 to receive the guide pins 140 that are carried by the frame 119 and are held from displacement by the cap 122. The latch member 138, as before stated, is made of corresponding halves for the reason that should one of the latch lugs 141 become broken, it will only become necessary to turn the latch 138 through 180°, when the other lug may be brought into operative position to enter the slot 22 of the rod 23 and thereby avoid the necessity of replacing the latch 138. In practice, the weight of the latch member determines the speed required to effect the latching and unlatching functions. In order to adjust the latch mechanism for different speeds differently weighted latch members will be employed, the latch members being readily interchangeable. The latch 138 is provided with an anti-friction bearing 137 by means of which it is connected with the sleeve 130 so that as the sleeve 130 is raised, the latch will be raised accordingly.

The oscillatable shaft construction, best shown in Fig. 3, which, *per se*, forms the subject-matter of my patent above referred to, includes the shaft 49 proper, which is mounted in plug bearings 143 at each end of the housing extension 4, and between which bearings the shaft 49 carries two sleeves 144, each of which has a head 145, at the end adjacent to the respective bearings 143. Each head 145 has a peripheral quarter circle groove 146, which receives the casing stop pin 147, to limit the turning motion of the sleeve in one direction. Each sleeve 144 is also provided with a longitudinal slot 148 terminating, adjacent to the head 145, in a circumferential quarter-turn groove 149, in which the shaft pin 150 rides. The torsion spring 151 encircles the sleeves 115 144 and has its ends respectively fitted into the recesses 152 of the respective heads 145.

In my improved construction, it will be observed that by the provision of the cam finger 53, all danger of breaking the same, should the shaft 49 be turned accidentally when the cam 10 is in alinement with the same, is avoided, for the reason that should the cam 10 be restored to the normal position while the shaft 49 is in its turned position, the cam finger 53 will yield over the cam 10 as the shaft 49 returns to its normal position. The pivoted head on the plunger will prevent breakage caused by jamming against the cam with which it co-

operates in the event that the cam is restored to the normal position while the plunger is out of the normal position.

From the foregoing description taken in connection with the accompanying drawings, it is thought the complete construction, operation and advantages of my invention will be readily understood by those skilled in the art to which it relates.

10. What I claim is:

1. In a system of the class described, a train carried apparatus including an air valve, means holding said valve closed, a device for releasing said holding means to permit said valve to open, means for resetting said holding means and thereby reclosing said valve, said releasing device including a plunger, said plunger including a main body portion, and a shoe united to the body portion by a connection that will break upon application of excessive stresses, and a tripping ramp for actuating said releasing device.

2. In a system of the class described, a train carried apparatus including an air valve, means holding said valve closed, a device for releasing said holding means to permit said valve to open, means for resetting said holding means and thereby reclosing said valve, said releasing device including a plunger, said plunger including a main body portion and a shoe, said shoe having provision for cutting loose snow and ice from the path of its movement, and a tripping ramp for actuating said releasing device.

3. In an apparatus of the class described, a train carried apparatus including an air valve, means holding said valve closed, a device for releasing said holding means to permit said valve to open, means for resetting said holding means to thereby reclose said valve, means located along the right of way for first actuating said releasing means, and then actuating said resetting means, said releasing means including a plunger and an ice and snow plow shoe carried by said plunger to clear the shoe path along the right of way from obstructions.

4. In an apparatus of the class described, a train carried apparatus including an air valve, means holding said valve closed, a device for releasing said holding means to permit said valve to open, means for resetting said holding means to thereby reclose said valve, means located along the right of way for first actuating said releasing means, and then actuating said resetting means, said releasing means including a plunger and a plow shoe carried by said plunger to clear the path of travel of the shoe.

5. In a system of the class described, a train carried apparatus including a support, an air valve mechanism, a connection

between said mechanism and the engineer's valve of the air brake system, a connection between said mechanism and the train pipe proper of the air brake system, said mechanism including an exhaust port, and valves for controlling communication between said connections and said port, a device carried by said support and connected with said valve mechanism for normally holding said mechanism to effect communication between said connections with the engineer's valve and the train pipe and cut off the exhaust duct, means cooperative with the aforesaid parts for releasing said valve mechanism to cut off the connection with the engineer's valve and bring said train pipe connection in communication with the exhaust duct to set the brakes, means cooperating with said device for resetting said valve mechanism, and devices located along the right of way for operating said releasing and said resetting means.

6. In a system of the class described, a train carried apparatus including an air valve, means holding said valve closed, a device for releasing said holding means to permit said valve to open, means for resetting said holding means and thereby reclosing said valve, means located along the right of way for actuating said releasing and said resetting means, and a manually operated resetting device including a rod, and a centrifugal governor and latch device for holding said rod non-operative above predetermined speeds, said last named device including a supporting casing, guides carried thereby, a weighted latch member mounted on said guides, a spindle, a sliding sleeve to engage said latch, and a ball device connecting said spindle and sleeve to raise said latch as the speed increases, said rod having a latch notch, said latch having a dog to engage the said rod, substantially as shown and described.

7. In a system of the class described, a train carried apparatus including an air valve, means holding said valve closed, a device for releasing said holding means to permit said valve to open, means for resetting said holding means and thereby reclosing said valve, means located along the right of way for actuating said releasing and said resetting means, and a manually operated resetting device including a rod, and a centrifugal governor and latch device for holding said rod non-operative above predetermined speeds, said last named device including a supporting casing, guides carried thereby, a reversible weighted latch member mounted on said guides, a spindle, a sliding sleeve to engage said latch, and a ball device connecting said spindle and sleeve to raise said latch as the speed increases, said rod having a latch notch, said

latch having a pair of dogs to engage the said rod one at a time according to the position of said latch.

8. In a train stopping apparatus, a support, a valve mechanism connectible with the air brake system and including a main air chamber, a train pipe air chamber, and an exhaust chamber, valve elements between said chambers, and a valve stem for engaging said valve elements, a rotatable shaft mounted in bearings in said support, means on said shaft for engaging said valve stem to hold said valve elements in their normal position, a cam member mounted on said shaft and including a plurality of cam elements, a reciprocating plunger, a head on said plunger for coöperation with one of said cam elements to move said shaft to release said valve elements, a resetting shaft, a trip arm carried by said resetting shaft, and a cam finger carried by said resetting shaft to coöperate with another of said cam elements to reset said cam shaft and thereby restore said valve elements to their normal position.

9. In a train stopping apparatus, a support, a valve mechanism connectible with the air brake system and including a main air chamber, a train pipe air chamber, and an exhaust chamber, valve elements between said chambers, and a valve stem for engaging said valve elements, a rotatable shaft mounted in bearings in said support, means on said shaft for engaging said valve stem to hold said valve elements in their normal position, a cam member mounted on said shaft and including a plurality of cam elements, a reciprocating plunger, a head on said plunger for coöperation with one of said cam elements to move said shaft to release said valve elements, a resetting shaft, a trip arm carried by said resetting shaft, a cam finger carried by said resetting shaft to coöperate with another of said cam elements to reset said cam shaft and thereby restore said valve elements to their normal position, said plunger having an air duct extending in its length, and a pipe connection between said duct and the train pipe air chamber of said valve mechanism, said valve elements of said valve mechanism adapted to normally effect communication between said main reservoir air chamber and said train pipe air chamber and when released to open communication between said train pipe air chamber and said exhaust chamber and close communication between said train pipe air chamber and said main reservoir air chamber.

10. In a train stopping apparatus, a support, a valve mechanism connectible with the air brake system and including a main air chamber, a train pipe air chamber, and an exhaust chamber, valve elements between said chambers, and a valve stem for engag-

ing said valve elements, a rotatable shaft mounted in bearings in said support, means on said shaft for engaging said valve stem to hold said valve elements in their normal position, a cam member mounted on said shaft and including a plurality of cam elements, a reciprocating plunger, a head on said plunger for coöperation with one of said cam elements to move said shaft to release said valve elements, a resetting shaft, a trip arm carried by said resetting shaft, a cam finger carried by said resetting shaft to coöperate with another of said cam elements to reset said cam shaft and thereby restore said valve elements to their normal position, said resetting shaft cam finger comprising a yieldable member adapted to yield in one direction, and means for holding said member in a normal position.

11. In a train stopping apparatus, a support, a valve mechanism connectible with the air brake system and including a main air chamber, a train pipe air chamber, and an exhaust chamber, valve elements between said chambers, and a valve stem for engaging said valve elements, a rotatable shaft mounted in bearings in said support, means on said shaft for engaging said valve stem to hold said valve elements in their normal position, a cam member mounted on said shaft and including a plurality of cam elements, a reciprocating plunger, a head on said plunger for coöperation with one of said cam elements to move said shaft to release said valve elements, a resetting shaft, a trip arm carried by said resetting shaft, a cam finger carried by said resetting shaft to coöperate with another of said cam elements to reset said cam shaft and thereby restore said valve elements to their normal position, said plunger having an air duct extending in its length, a pipe connection between said duct and the train pipe air chamber of said valve mechanism, said valve elements of said mechanism adapted to normally effect communication between said main reservoir air chamber and said train pipe air chamber and when released to open communication between said train pipe air chamber and said exhaust chamber and close communication between said train pipe air chamber and said main reservoir air chamber, said resetting shaft cam finger comprising a yieldable member adapted to yield in one direction, and means for holding said member in a normal position.

12. In a train stopping apparatus, a support, a valve mechanism connectible with the air brake system and including a main air chamber, a train pipe air chamber, and an exhaust chamber, valve elements between said chambers, and a valve stem for engaging said valve elements, a rotatable shaft mounted in bearings in said support, means on said shaft for engaging said valve stem

- to hold said valve elements in their normal position, a cam member mounted on said shaft and including a plurality of cam elements, a reciprocating plunger, a head on 5 said plunger for coöperation with one of said cam elements to move said shaft to release said valve elements, a resetting shaft, a trip arm carried by said resetting shaft, a cam finger carried by said resetting shaft, 10 to coöperate with another of said cam elements to reset said cam shaft and thereby restore said valve elements to their normal position, said plunger head including a member secured to the plunger, an extension 15 pivoted to said member and adapted to coöperate with said cam and means for holding said extension and said head member in normal contact.
13. In a train stopping apparatus, a support, 20 a valve mechanism connectible with the air brake system and including a main air chamber, a train pipe air chamber, and an exhaust chamber, valve elements between said chambers, and a valve stem for engaging said valve elements, a rotatable shaft mounted in bearings in said support, means on said shaft for engaging said valve stem to hold said valve elements in their normal position, a cam member mounted on said 25 shaft and including a plurality of cam elements, a reciprocating plunger, a head on said plunger for coöperation with one of said cam elements to move said shaft to release said valve elements, a resetting shaft, 30 a trip arm carried by said resetting shaft, a cam finger carried by said resetting shaft to coöperate with another of said cam elements to reset said cam shaft and thereby restore said valve elements to their normal position, said resetting shaft cam finger comprising a yieldable member adapted to yield in one 35 direction, means for holding said member in a normal position, said plunger head including a member secured to the plunger, an extension pivoted to said member and adapted to coöperate with said cam, and 40 means for holding said extension and said head member in normal contact.
15. In a train stopping apparatus, a support, a valve mechanism connectible with the air brake system and including a main air chamber, a train pipe air chamber, and an exhaust chamber, valve elements between said chambers, and a valve stem for engaging said valve elements, a rotatable shaft mounted in bearings in said support, means 45 on said shaft for engaging said valve stem to hold said valve elements in their normal position, a cam member mounted on said shaft and including a plurality of cam elements, a reciprocating plunger, a head on said plunger for coöperation with one of said cam elements to move said shaft to release said valve elements, a resetting shaft, 50 a trip arm carried by said resetting shaft, a cam finger carried by said resetting shaft to coöperate with another of said cam elements to reset said cam shaft and thereby restore said valve elements to their normal 55 position, said plunger having an air duct extending in its length, a pipe connection between said duct and the train pipe air chamber of said valve mechanism, said valve elements of said valve mechanism adapted to normally effect communication between said main reservoir air chamber and said train pipe air chamber and when released to open communication between said train pipe air chamber and said exhaust chamber 60 and close communication between said train pipe air chamber and said main reservoir air chamber, said plunger head including a member secured to the plunger, an extension pivoted to said member and adapted to coöperate with said cam, and means for holding said extension and said head member in normal contact.
14. In a train stopping apparatus, a support, a valve mechanism connectible with the air brake system and including a main air chamber, a train pipe air chamber, and an exhaust chamber, valve elements between said chambers, and a valve stem for engaging said valve elements, a rotatable shaft 65 mounted in bearings in said support, means
- on said shaft for engaging said valve stem to hold said valve elements in their normal position, a cam member mounted on said shaft and including a plurality of cam elements, a reciprocating plunger, a head on said plunger for coöperation with one of said cam elements to move said shaft to release said valve elements, a resetting shaft, a trip arm carried by said resetting shaft, a cam finger carried by said resetting shaft to 70 coöperate with another of said cam elements to reset said cam shaft and thereby restore said valve elements to their normal position, said resetting shaft cam finger comprising a yieldable member adapted to yield in one 75 direction, means for holding said member in a normal position, said plunger head including a member secured to the plunger, an extension pivoted to said member and adapted to coöperate with said cam, and 80 means for holding said extension and said head member in normal contact.
16. In a train stopping apparatus, a support, a valve mechanism connectible with the air brake system and including a main air chamber, a train pipe air chamber, and an exhaust chamber, valve elements between said chambers, and a valve stem for engaging said valve elements, a rotatable shaft 85 mounted in bearings in said support, means
- on said shaft for engaging said valve stem to hold said valve elements in their normal position, a cam member mounted on said shaft and including a plurality of cam elements, a reciprocating plunger, a head on said plunger for coöperation with one of said cam elements to move said shaft to release said valve elements, a resetting shaft, a trip arm carried by said resetting shaft, a cam finger carried by said resetting shaft to 90 coöperate with another of said cam elements to reset said cam shaft and thereby restore said valve elements to their normal position, said resetting shaft cam finger comprising a yieldable member adapted to yield in one 95 direction, means for holding said member in a normal position, said plunger head including a member secured to the plunger, an extension pivoted to said member and adapted to coöperate with said cam, and 100 means for holding said extension and said head member in normal contact.
17. In a train stopping apparatus, a support, a valve mechanism connectible with the air brake system and including a main air chamber, a train pipe air chamber, and an exhaust chamber, valve elements between said chambers, and a valve stem for engaging said valve elements, a rotatable shaft 105 mounted in bearings in said support, means
- on said shaft for engaging said valve stem to hold said valve elements in their normal position, a cam member mounted on said shaft and including a plurality of cam elements, a reciprocating plunger, a head on said plunger for coöperation with one of said cam elements to move said shaft to release said valve elements, a resetting shaft, a trip arm carried by said resetting shaft, a cam finger carried by said resetting shaft to 110 coöperate with another of said cam elements to reset said cam shaft and thereby restore said valve elements to their normal position, said resetting shaft cam finger comprising a yieldable member adapted to yield in one 115 direction, means for holding said member in a normal position, said plunger head including a member secured to the plunger, an extension pivoted to said member and adapted to coöperate with said cam, and 120 means for holding said extension and said head member in normal contact.
18. In a train stopping apparatus, an air valve adapted to be connected with the air brake system, a valve controlling mechanism including a cam shaft, and means on said shaft for coöoperating with said valve, a multiple cam on said cam shaft, an operating plunger having a yielding head to engage one of the cam elements of said 125 multiple cam to turn said cam shaft in one 130 direction, means for holding said member in a normal position, said plunger head including a member secured to the plunger, an extension pivoted to said member and adapted to coöperate with said cam, and means for holding said extension and said head member in normal contact.

direction, a resetting shaft, a cam finger pivoted to said resetting shaft for engaging another of said cam elements to reset said cam shaft, said cam shaft including an arm, a latch for engaging said arm, and a manual resetting device including a reciprocating rod for coöperation with said arm to reset said cam shaft.

17. In an apparatus of the class described, a valve mechanism connectible with the train pipe of an air brake system, a cam shaft including means coöperative with said valve mechanism for holding said valve mechanism in the normal position and for releasing said valve mechanism when said cam shaft is turned, a multiple cam on said cam shaft, a reciprocating plunger coöperative with one of the cam elements of said multiple cam, a resetting shaft, a yieldable cam finger on said resetting shaft coöperative with another of said cam elements, and means holding said cam shaft against accidental displacements.

18. In an apparatus of the class described, a valve mechanism connectible with the train pipe of an air brake system, a cam shaft including means coöperative with said valve mechanism for holding said valve mechanism in the normal position and for releasing said valve mechanism when said cam shaft is turned, a multiple cam on said cam shaft, a reciprocating plunger coöperative with one of the cam elements of said multiple cam, a resetting shaft, a yieldable cam finger on said resetting shaft coöperative with another of said cam elements, means holding said cam shaft against accidental displacement, said plunger including a stem, a collar threaded onto said stem, a head member pivoted to said collar and yieldable in one direction, a leaf spring carried by said collar and engaging said stem to prevent swiveling of said collar, said leaf spring engaging said head to normally retain said head and said collar in contact.

19. In a train stopping apparatus, a support, a valve mechanism connectible with the air brake system and including a main air chamber, a train pipe air chamber, and an exhaust chamber, valve elements between said chambers, and a valve stem for engaging said valve elements, a rotatable shaft mounted in bearings in said support, means on said shaft for engaging said valve stem to hold said valve elements in their normal position, a cam member mounted on said shaft and including a plurality of cam elements, a reciprocating plunger, a head on said plunger for coöperation with one of said cam elements to move said shaft to release said valve elements, a resetting shaft, a trip arm carried by said resetting shaft, a cam finger carried by said resetting shaft to coöperate with another of said cam elements to reset said cam shaft and thereby

restore said valve elements to their normal position, substantially as shown and for the purposes described.

20. In a train stopping apparatus, a support, a valve mechanism connectible with the air brake system and including a main air chamber, a train pipe air chamber, and an exhaust chamber, valve elements between said chambers, and a valve stem for engaging said valve elements, a rotatable shaft mounted in bearings in said support, means on said shaft for engaging said valve stem to hold said valve elements in their normal position, a cam member mounted on said shaft and including a plurality of cam elements, a reciprocating plunger, a head on said plunger for coöperation with one of said elements to move said shaft to release said valve elements, a resetting shaft, a trip arm carried by said resetting shaft, a cam finger carried by said resetting shaft to coöperate with another of said cam elements to reset said cam shaft and thereby restore said valve elements to their normal position, said resetting shaft cam finger comprising a yieldable member adapted to yield in one direction, and means for holding said member in a normal position.

21. In a train stopping apparatus, a support, a valve mechanism connectible with the air brake system and including a main air chamber, a train pipe air chamber, and an exhaust chamber, valve elements between said chambers, and a valve stem for engaging said valve elements, a rotatable shaft mounted in bearings in said support, means on said shaft for engaging said valve stem to hold said valve elements in their normal position, a cam member mounted on said shaft and including a plurality of cam elements, a reciprocating plunger, a head on said plunger for coöperation with one of said cam elements to move said shaft to release said valve elements, a resetting shaft, a trip arm carried by said resetting shaft, a cam finger carried by said resetting shaft to coöperate with another of said cam elements to reset said cam shaft and thereby restore said valve elements to their normal position, said plunger head including a member secured to the plunger, and an extension pivoted to said member and adapted to coöperate with said cam.

22. In a train stopping apparatus, a support, a valve mechanism connectible with the air brake system and including a main air chamber, a train pipe air chamber, and an exhaust chamber, valve elements between said chambers, and a valve stem for engaging said valve elements, a rotatable shaft mounted in bearings in said support, means on said shaft for engaging said valve stem to hold said valve elements in their normal position, a cam member mounted on said shaft and including a plurality of cam ele-

ments, a reciprocating plunger, a head on said plunger for coöperation with one of said cam elements to move said shaft to release said valve elements, a resetting shaft, a trip arm carried by said resetting shaft, a cam finger carried by said resetting shaft to coöperate with another of said cam elements to reset said cam shaft and thereby restore said valve elements to their normal position, said plunger head including a member secured to the plunger, an extension pivoted to said member and adapted to coöperate with said cam.

23. In a train stopping apparatus, a support, a valve mechanism connectible with the air brake system and including a main air chamber, a train pipe air chamber, and an exhaust chamber, valve elements between said chambers, and a valve stem for engaging said valve elements, a rotatable shaft mounted in bearings in said support, means on said shaft for engaging said valve stem to hold said valve elements in their normal position, a cam member mounted on said shaft and including a plurality of cam elements, a reciprocating plunger, a head on said plunger for coöperation with one of said cam elements to move said shaft to release said valve elements, a resetting shaft, a trip arm carried by said resetting shaft, a cam finger carried by said resetting shaft to coöperate with another of said cam elements to reset said cam shaft and thereby restore said valve elements to their normal position, said resetting shaft cam finger comprising a yieldable member adapted to yield in one direction, said plunger head including a member secured to the plunger, and an extension pivoted to said member and adapted to coöperate with said cam.

24. In a train stopping apparatus, an air valve adapted to be connected with the air brake system, a valve controlling mechanism including a cam shaft, and means on said shaft for coöperating with said valve, a multiple cam on said cam shaft, an operating plunger having a yielding head to engage one of the cam elements of said multiple cam to turn said cam shaft in one direction, a resetting shaft, a cam finger yieldably mounted on said resetting shaft for engaging another of said cam elements to reset

said cam shaft, said cam including an arm, a latch for engaging said arm.

25. In a train stopping apparatus, an air valve adapted to be connected with the air brake system, a valve controlling mechanism including a cam shaft, and means on said shaft for coöperating with said valve, a multiple cam on said cam shaft, an operating plunger having a yielding head to engage one of the cam elements of said multiple cam to turn said cam shaft in one direction, a resetting shaft, a cam finger yieldably mounted on said resetting shaft for engaging another of said cam elements to reset said cam shaft.

26. In an apparatus of the class described, a valve mechanism connectible with the train pipe of an air brake system, a cam shaft including means coöperating with said valve mechanism for holding said valve mechanism in the normal position and for releasing said valve mechanism when said cam shaft is turned, a multiple cam on said cam shaft, a reciprocating plunger coöperating with one of the cam elements of said multiple cam, a resetting shaft, a yieldable cam finger on said resetting shaft coöperative with another of said cam elements.

27. In a train stopping apparatus, the combination with an air valve, a valve controlling mechanism including a shaft, a releasing device, a resetting device, both of said devices being normally disconnected from said shaft, said releasing device including a movable body and a yieldable member mounted on said movable body and adapted to yield in the event that said resetting device is operated, while said releasing device is out of its normal position, said resetting device including a member adapted, when moved, to operatively engage said shaft to restore the same.

28. In an apparatus of the character stated, an operating shaft, a cam thereon, an operating plunger including a yieldable head to coöperate with said cam, and means for resetting said cam shaft to its initial position.
